US00D961582S

(12) **United States Design Patent** (10) Patent No.: **US D961,582 S**
Graber et al. (45) Date of Patent: **** Aug. 23, 2022**

(54) **RING-SHAPED ELECTRONIC DEVICE**

(71) Applicant: **Amazon Technologies, Inc.**, Seattle, WA (US)

(72) Inventors: **Sarah Graber**, Seattle, WA (US); **Sun Joo Han**, San Francisco, CA (US); **Bernhard Wildner**, San Francisco, CA (US); **Adrian Napolis**, Bellevue, WA (US); **Ulf Jan-Ove Mattsson**, Campbell, CA (US); **Felipe A. Varela**, San Jose, CA (US); **Albert John Yu Sam Chua**, San Jose, CA (US)

(73) Assignee: **AMAZON TECHNOLOGIES, INC.**, Seattle, WA (US)

(**) Term: **15 Years**

(21) Appl. No.: **29/706,056**

(22) Filed: **Sep. 17, 2019**

(51) LOC (13) Cl. **14-02**

(52) U.S. Cl.

USPC **D14/344**

(58) **Field of Classification Search**

(57) **CLAIM**

The ornamental design for a ring-shaped electronic device, as shown and described.

DESCRIPTION

FIG. 1 is an upper right side perspective view of a ring-shaped electronic device.

FIG. 2 is an upper left side perspective view showing the design of FIG. 1.

FIG. 3 is a lower left side perspective view showing the design of FIG. 1.

FIG. 4 is a lower right side perspective view showing the design of FIG. 1.

FIG. 5 is a left side view showing the design of FIG. 1.

FIG. 6 is a right side view showing the design of FIG. 1.

FIG. 7 is a front perspective view showing the design of FIG. 1.

FIG. 8 is a top view showing the design of FIG. 1; and,

FIG. 9 is a bottom view showing the design of FIG. 1. The broken lines are for purposes of illustration only and do not form a part of the claimed designs.

1 Claim, 8 Drawing Sheets
